US0D1110977S

(12) **United States Design Patent** (10) **Patent No.:** **US D1,110,977 S**
(45) **Date of Patent:** **** Feb. 3, 2026**

(54) **SUSCEPTOR**

(71) Applicant: **NuFlare Technology, Inc.**, Kanagawa (JP)

(72) Inventors: **Takafumi Kido**, Kawasaki (JP); **Masataka Iwasaki**, Kawasaki (JP); **Takuto Umetsu**, Kamakura (JP)

(73) Assignee: **NuFlare Technology, Inc.**, Kanagawa (JP)

(**) Term: **15 Years**

(21) Appl. No.: **29/954,966**

(22) Filed: **Jul. 30, 2024**

(30) **Foreign Application Priority Data**

Feb. 13, 2024 (JP) ..... 2024-002982 D

(51) **LOC (15) Cl.** **13-03**

(52) **U.S. Cl.** ..... **USPC D13/182**

(58) **Field of Classification Search**

(57) **CLAIM**

The ornamental design for a susceptor as shown and described.

DESCRIPTION

FIG. 1 is a front perspective view of a susceptor showing our new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a cross sectional view taken along line 9-9 in FIG. 3.

1 Claim, 7 Drawing Sheets
